UNITED STATES PATENT OFFICE.

HOWARD N. JONES, OF PAWTUXET, RHODE ISLAND, ASSIGNOR OF ONE-HALF TO
JOSEPH LEROY JONES, OF WINTHROP, MASSACHUSETTS.

DOOR LATCH.

Application filed November 18, 1925. Serial No. 69,798.

This invention relates to an improved construction of door fastening mechanism more particularly adapted for use on vehicle doors, such as automobiles and the like; and the object of this invention is to provide a door fastening mechanism such as a latch and the like which is mounted to wedge between the edge of the door and the door jamb portion to hold the door closed and at the same time bind the door securely against rattling.

A further object of the invention is to provide converging binding plates on the door jamb and on the door and to provide a locking roll or other member which is adapted to be moved to wedge between these converging surfaces to hold the door closed and bind the same against rattling.

With these and other objects in view, the invention consists of certain novel features of construction, as will be more fully described, and particularly pointed out in the appended claims.

In the accompanying drawings:

Figure 1 is a sectional edge view of the door in closed position showing the converging binding plates in the door jamb and the door with the latch roll wedged between.

Figure 2 shows the latch as having been withdrawn and the door as starting back from its closed position.

Figure 3 is a side elevation showing the double cone shaped wedge roll as mounted on the inclined V-shaped wedging plate on the door.

Figure 4 is a detail of the double cone shaped wedge roll.

Figure 5 is a perspective view of the pivoted arm on which the roll is carried.

Figure 6 is a perspective view of the V-shaped wedge plate which is carried by the door and against which the wedge roll jams to bind the door.

Figure 7 is a perspective view of the striker plate carried by the door jamb.

It is found in practice that doors used on automobiles, due to the constant jars, are inclined to work loose and rattle to the annoyance of the occupants of the car and to prevent this rattling of the door, I have provided a wedging latch member on the door to lock the same closed and also to securely bind the door against rattling regardless of the amount of vibration to which the car

may be subjected; and the following is a detailed description of the present embodiment of my invention and showing one arrangement of latch and wedging mechanism by which these advantageous results may be accomplished:-

With reference to the drawings, 10 designates the door jamb member of the door frame as carrying a plate 11 which is set on an incline to the front face of the jamb. In 15 the meeting edge 12 of the door 13 is mounted a wedge plate 14 herein shown as being V-shaped in cross section, which plate is set on an angle to converge with the striker plate 11 in the door jamb when the door is in closed position. This wedge plate 14 is preferably V-shape in cross section, as best illustrated in Figure 3, to receive the double conical wedge roll 15, which roll is operatively mounted in a slot 24 in the arm 16 which is pivoted at 17 to extend through and be guided in the slot 23 in the plate 14, and which arm is acted upon and pressed endways by the spring 18 to hold the wedge roll in contact with its inclined plate 14, and 20 this arm is slotted at 25 at its pivot point to permit an endways movement thereof as the roll follows the inclined surface of its wedge plate 14.

A second compression spring 19 is arranged to act against the back of this arm 16 to normally force the roll inwardly towards binding position. In order to operate or move this roll from gripping or binding position, I have provided a door knob 20 on the outside of the door in which is formed a push pin 21 an inward pressure on which serves to move the wedge roll from binding position releasing the door to be opened; also I have shown an operating handle 22 on the inner face of the door which may be forced inwardly to withdraw the wedge roll from its binding position.

My improved door fastening mechanism is very simple and practical in construction 100 and is effective in its operation and when the door is closed the jar of the vehicle serves to force the wedging roll under action of the spring 19 to lock the door and to also more firmly wedge and bind the door against 105 rattling.

I have herein shown the binding plate on the door as V-shape in cross section for guiding the wedging roll laterally, I do not, however, wish to be restricted to this par- 110

ticular shape of plate as a plate of any desired shape in cross section may be employed, also I have shown a wedging roll of a double tapering shape but a roll of any desired shape may be employed without departing from the spirit and scope of my invention.

The foregoing description is directed solely towards the construction illustrated, but 10 I desire it to be understood that I reserve the privilege of resorting to all the mechanical changes to which the device is susceptible, the invention being defined and limited only by the terms of the appended claims.

15 I claim:

1. In a door fastening mechanism, a door frame having a jamb portion, a door having an edge mounted to swing into adjacency with said jamb, and a rotatably mounted member on one of said parts and positioned to wedge between portions of said door and portions of the door frame jamb to bind the door when closed.

2. In a door fastening mechanism, a door jamb portion, a door having an edge portion mounted to swing into position opposite said jamb, and a member mounted on one of said portions carrying a pivot with a binding roll thereon to move between portions of the door 30 and portions of said door jamb to bind the door when closed.

3. In a door fastening mechanism, a door jamb portion, a door having an edge portion mounted to swing into position opposite said jamb, said door jamb and edge having converging portions, and a lock member mounted to be moved to wedge between said converging surfaces to bind the door when closed.

4. In a door fastening mechanism, a door jamb portion, a door having an edge portion mounted to swing into position opposite said jamb, said door jamb and edge portion having converging portions, and a locking roll mounted to be moved to wedge between said converging surfaces to bind the door when closed.

5. In a device for fastening a door mounted to swing in adjacency with the door jamb, comprising cooperating converging pressure plates on the door and jamb portions, and a wedging roll mounted to be moved between said plates to bind the door when closed.

6. In a device for fastening a door mounted to swing in adjacency with the door jamb, comprising cooperating converging pressure plates on the door and jamb portion, and a wedging roll mounted to swing into position between said plates to bind the door when closed.

7. In a device for fastening a door mounted to swing in adjacency with the door jamb, comprising cooperating converging pressure plates on the door and jamb portions, a wedging roll mounted to swing between said

plates, and a spring forcing said roll to wedge between said plates to lock the door and bind it when closed.

8. In a device for fastening a door, mounted to swing in adjacency with a door jamb, 70 comprising cooperating converging pressure plates on the door and jamb portions, a guided swinging arm mounted in the door, a spring-pressed wedging roll carried by said arm to swing between said plates to lock the door and bind it against rattling when closed.

9. In a device for fastening a door mounted to swing in adjacency with the door jamb, 75 a latch plate on the door V-shaped in cross section and positioned to cooperate with said striker plate, and a double tapered roll carried by the door to be moved between said plates to wedge and bind the door against rattling when closed.

10. In combination with a door and door jamb portion of the door frame, the edge of the door being arranged to swing into the jamb portion when closed, cooperating binding plates on the door and door jamb 80 and a tapering binding roll carried by the door to roll between said plates and bind the door when closed.

11. In combination with a door and door jamb portion, the edge of the door being arranged to swing into the jamb portion of the door frame when closed, cooperating converging binding plates on the door and door jamb, one of said plates being V-shaped in 100 cross section, and a binding roll shaped to fit said V-plate to roll between said plates and bind the door when closed.

12. In combination with a swinging door, the edge portion of which is in adjacency with the jamb portion of the door frame 105 when closed, a door fastening mechanism comprising plates inset into each of said portions to be in converging planes, a movably mounted member between said plates, and yielding means for forcing said member towards the convergence of said plates to bind the door against movement towards the door jamb.

13. In combination with a swinging door, the edge portion of which is in adjacency with the jamb portion of the door frame when closed, a door fastening mechanism comprising an arm carried by the door and mounted to have a relative yielding swinging and endways movement therewith, and a 110 member carried by said arm to cooperate with said portions to wedge said door against a movement towards the door jamb.

14. In combination with a door and door jamb portion, the edge of the door being arranged to swing into the jamb when closed, cooperating binding plates on the door and door jamb, a spring pressed binding roll mounted to be positioned between the door edge and door jamb for wedging the door 125 130

when closed, and an operating handle for moving the roll to release the door.

15. In combination with a door and door jamb portion, the edge of the door being arranged to swing into the jamb when closed, cooperating binding plates on the door and door jamb, a spring pressed binding roll mounted to be positioned between the door edge and door jamb for wedging the door when closed, handles operable from either side of the door for moving the roll to release the door, and handles operable from either side of the door for moving the roll to release the door.

16. In combination with a door and door jamb portion, the edge of the door being ar-

ranged to swing into the jamb when closed, 15 cooperating converging binding plates on the door and door jamb, a binding roll mounted to be positioned between the door edge and door jamb for wedging the door when closed, handles operable from either side of the door for moving the roll to release the door, 20 and a spring for forcing said roll to wedge between said plates to prevent the door from rattling when said handles are released and the door closed. 25

In testimony whereof I affix my signature.

HOWARD N. JONES.
